HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 12,487, dated September 20, 1881.

Application filed August 9, 1881. Term of patent 3½ years.

To all whom it may concern:

Be it known that I, HENRY HUNT, of Greenville, in the county of Hudson and State of New Jersey, have invented a new and original 5 Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

A is a figure, of very irregular outline, placed near a figure, B, whose upper part is an ob-

liquely-placed rectangle. Above figure B is another irregular figure, C, and below the figure B is a field, D, containing sundry irregular ornaments. Below figure A is a figure, E, of approximately-pentagonal outline. These figures and the spaces between them have sundry fantastic ornaments, as shown.

I claim—

The design for carpets, consisting of the figures A B C D E, substantially as shown.

HENRY HUNT.
